UNITED STATES PATENT OFFICE.

WILLIAM E. SAYERS, OF NEW YORK, N. Y., ASSIGNOR TO THE HARTFORD CARPET CORPORATION, A CORPORATION OF CONNECTICUT.

DESIGN FOR CARPET.

SPECIFICATION forming part of Design No. 37,109, dated August 30, 1904.

Application filed May 16, 1904. Serial No. 208,320. Term of patent 3½ years.

To all whom it may concern:

Be it known that I, WILLIAM E. SAYERS, a citizen of the United States, and a resident of the borough of Brooklyn, in the county of 5 Kings, city of New York, and State of New York, have invented a new, original, and ornamental Design for Carpet, of which the following is a specification.

The figure of my new and original design, 10 as shown in the accompanying drawing, illustrates a section of a carpet having said design thereon.

What I claim as new, and desire to secure by Letters Patent, is—

The ornamental design for a carpet substantially as shown. 15
